(57) **CLAIM**

The ornamental design for a smartwatch, as shown and described.

DESCRIPTION

FIG. 1 is a front and right side perspective view of a smartwatch showing our new design;
FIG. 2 is a rear and left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is an enlarged top plan view thereof;
FIG. 8 is an enlarged bottom plan view thereof;
FIG. 9 is an enlarged view of an encircled portion of the smartwatch labeled 9 in FIG. 1;
FIG. 10 is an enlarged view of an encircled portion of the smartwatch labeled 10 in FIG. 3; and,
FIG. 11 is an enlarged view of an encircled portion of the smartwatch labeled 11 in FIG. 4.
The broken lines shown in the drawings represent portions of the smartwatch that form no part of the claimed design. The dot-dash broken lines encircling portions of the smartwatch in FIGS. 1, 3 and 4 and illustrated in enlarged views in FIGS. 9, 10 and 11 form no part of the claimed design.

1 Claim, 11 Drawing Sheets
